UNITED STATES PATENT OFFICE.

WILLIAM I. THOMSON, OF NEWARK, NEW JERSEY, ASSIGNOR TO SAFETY CAR HEATING & LIGHTING COMPANY, A CORPORATION OF NEW JERSEY.

LIGHTING SYSTEM.

No. 926,518.

Specification of Letters Patent.

Patented June 29, 1909.

Application filed April 15, 1903. Serial No. 152,648.

To all whom it may concern:

Be it known that I, WILLIAM I. THOMSON, residing at Newark, in the county of Essex and State of New Jersey, have invented certain new and useful Improvements in Lighting Systems, of which the following is a full, clear, and exact description, such as will enable others skilled in the art to which it appertains to make and use the same.

10 The invention relates to a system especially adapted for what is known as car axle lighting wherein the electricity which supplies the lamps is generated by a dynamo mounted upon or driven from the car axle. 15 It is, however, capable of use in a variety of relations.

One of the objects thereof is to provide a means whereby the output of the dynamo is self-regulatable or controlled in accordance 20 with the speed of the train.

Other objects and advantages will appear hereinafter.

The invention accordingly consists in the features of construction, combinations of elements, arrangement of parts and inter-relations of the system, which will be herein-after more fully described and the novel features thereof pointed out in the claims.

In the accompanying drawings, Figure 1 30 illustrates diagrammatically a system embodying the invention. Fig. 2 is a detail showing a modification of certain of the elements of the system shown in Fig. 1.

Similar reference characters refer to similar 35 parts throughout the several views.

The lamps and storage battery of a car lighting system are indicated at 1 and 2 respectively as embodied in the main circuit of a dynamo 3 which is preferably driven, either 40 directly or indirectly, from a car axle. The leads of this main circuit are represented at 4, 5, 6 and 7, a switch being interposed at 8 and the coils of a solenoid 9 being interposed between the leads 6 and 7.

45 The function of switch 8 is, as will be obvious from the drawings, to open the circuit through the dynamo 3 and prevent any wasteful discharge of battery 2. The coils of the field magnet or magnets of the dynamo 50 are represented at 10 as shunt-wound, the leads of the shunt circuit being indicated at 11 and 12. Embodied in this shunt field circuit is a variable resistance which is illustrated as comprising a pile or series of carbon 55 disks or other contacting electrodes 13 lo-

cated between the plates 14 and 15 to which the leads 11 and 12 are connected. The lower of these plates is stationary and the upper one is carried by an insulated arm 16 pivotally connected to the end of the lever 17 pivotally mounted at 18. To the other end of this lever is pivotally connected the plunger 19 of the solenoid 9. A retractile spring 20 tends to rock the lever 17 on its pivot so as to increase the pressure of the plate 14 on the pile of carbon disks, thereby lessening the resistance of such pile and the resistance of the field circuit of the dynamo. There is also preferably provided a means for absorbing any sudden movements or jerks of the lever 17, as a dash-pot 20^a having its piston 21 connected to one of the arms of the lever.

The operation and advantages of such a system will be apparent to those acquainted with the art, but they may be briefly summarized. The dynamo gives its normal output at a certain train speed. The parts should be so adjusted that as the speed increases the increased current in the main circuit causes the plunger of the solenoid to be 8 drawn down, thus diminishing the pressure on the pile of carbon disks and increasing the resistance of the field of the dynamo. The variations of resistance of the pile of carbon disks due to slight variations in pressure 8 are so great that a very slight movement of the solenoid will be sufficient to react strongly upon the dynamo and to compensate for the increase in speed. At low train speeds the carbons will be pressed tightly together by 9; the action of the retractile spring, thus enabling the dynamo to build up rapidly.

It will be apparent that this system provides means whereby a source of energy adapted to supply a current for any desired 9; use may be caused to react upon itself in order to regulate the amount of energy supplied, thereby tending always to bring the output of such energy to normal. The advantages of such a self-regulatable system, 10 both general and specific, will be clear without elaboration. Certain advantages to be noted, however, reside in the fact that with the proposed system I am enabled to regulate satisfactorily the output of a shunt 10 wound dynamo, with a field produced by a single circuit only, thereby doing away with the complicated wiring of other systems, wherein the field is a compound one embodying differential series coils and the like. This 11

facility of regulation is due, among other things to the peculiar advantages of the variable resistance device which I use and to the fact that the shunt circuit in which said 5 resistance is introduced is taken off from the main circuit, as shown; at points nearer to the dynamo than the point at which the solenoid is introduced in the main circuit, so that the field circuit may be said to be independent of the controlling device in the main 10 circuit.

It will be obvious that the invention is not limited to the details shown in the present embodiment, as various changes may be 15 made in the system illustrated without departing from the scope of the invention. For example, there may be substituted for the carbon disks carbon in granulated or other form, or other material whose resistance 20 changes with pressure.

Fig. 2 shows a modified arrangement of the carbon disks, wherein such disks are in two piles with one of the leads of the field circuit of the dynamo connected to each of the piles, 25 the two piles being connected by a conducting arm 22, which conducting arm is carried from the end of the lever 17. By this arrangement, a given motion of the solenoid plunger will produce a greater change in the 30 resistance of the field circuit and a more sensitive and quickly responsive action is obtained.

Having described my invention, what I claim as new and desire to secure by Letters 35 Patent is:—

1. In combination, a shunt wound generator having serially included in its field circuit a plurality of contacting electrodes and positively acting electromagnetic means controlled by the current output of the generator for varying the pressure with which said 10 electrodes contact.

2. In a car axle lighting system, in combination, a dynamo adapted to be driven from 15 a car axle, said dynamo having a single field

circuit shunt wound from the main circuit, a variable resistance device included in said field circuit, said device embodying a material whose resistance varies with pressure, a controlling device in series with the main circuit of the dynamo, said controlling device adapted to be operated by variations of current in said main circuit, and connections from said controlling device for varying the pressure on said resistance device. 50

3. In a car axle lighting system, in combination, a dynamo adapted to be driven from a car axle, said dynamo having a field circuit shunt wound from the main circuit, a series of carbon disks interposed in said field circuit, a controlling device adapted to be actuated by variations in current in the main circuit of the dynamo and in series therewith, a connection between said controlling device and said disks such that pressure on said disks 60 is decreased as the current in the main circuit increases, and a spring acting upon said disks in opposition to said controlling device to increase the pressure thereon. 65

4. In a car axle lighting system, in combination, a dynamo adapted to be driven from a car axle, said dynamo having a field circuit shunt wound from the main circuit, a series of carbon disks included in said field circuit, a solenoid in series with the main circuit of the dynamo and independent of the field circuit, a connection between the plunger of 70 said solenoid and said disks such that the pressure upon said disks is decreased as the current in the main circuit increases, and a spring adapted to act upon said disks to increase the pressure thereon in opposition to said solenoid. 75

In testimony whereof I affix my signature, in the presence of two witnesses.

WILLIAM I. THOMSON.
